FIG. 1 is a perspective view from above of an electro-surgical cautery instrument showing my new design;

FIG. 2 is a front elevational view taken on line 2—2 of FIG. 1;

FIG. 3 is a rear elevational view of the instrument of FIG. 1;

FIG. 4 is a top plan view of the instrument of FIG. 1;

FIG. 5 is a side elevational view of the instrument of FIGS. 1 and 4, the forward half of which is essentially symmetrical about a longitudinal center line;

FIG. 6 is a bottom plan view of the cautery instrument shown in FIGS. 1, 4 and 5;

FIGS. 7, 8 and 9 are cross-sectional views as taken substantially on lines 7—7, 8—8, and 9—9 of FIG. 5;

FIG. 10 is a cross-sectional view taken on line 10—10 of FIG. 6;

FIG. 11 is a fragmentary side elevational view of the rearward position of the instrument as viewed on line 11—11 of FIG. 4;

FIG. 12 is a side elevational view of a modified embodiment of the form disclosed in FIGS. 1—11 inclusive;

FIG. 13 is a perspective of a further modified embodiment illustrated in FIG. 1;

FIG. 14 is a side elevational view of the embodiment disclosed in FIG. 13;

FIG. 15 is an end elevational view of the rearward portion of the handle of the embodiment depicted in FIGS. 13 and 14;

FIG. 16 is a fragmentary elevational view of the rearward portion of the body, as viewed from the side opposite that shown in FIG. 13;

FIG. 17 is a perspective view from above depicting a further modification of the form shown in FIG. 1;

FIG. 18 is a bottom plan view of the modified form of FIG. 17; and

FIG. 19 is a side elevational view of the embodiment depicted in FIGS. 17 and 18, as viewed on line 19—19 of FIG. 17.

The broken lines are shown for illustrative purposes only.

I claim:

The ornamental design for an electrosurgical cautery instrument, as shown and described.
